Primary Examiner—Cathron C. Brooks

Assistant Examiner—Austin Murphy

(57) **CLAIM**

The ornamental design for a mail delivery transmitter and receiver, as shown.

DESCRIPTION

FIG. 1 is a front elevational view showing my new design of the mail delivery transmitter and receiver;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front isometric view thereof; and,

FIG. 8 is an isometric view of the transmitter button portion of my design, shown separately to illustrate its position of use.

The broken lines shown in the drawings form no part of the claimed design.

1 Claim, 4 Drawing Sheets

FIG. 3

FIG. 4

FIG. 5

FIG. 6

FIG. 7
